PHONOGRAPH

Charles Huenlich, Bloomfield, N. J., assignor to
 Thomas A. Edison, Incorporated, West Orange,
 N. J., a corporation of New Jersey

Application March 22, 1941, Serial No. 384,636

15 Claims. (Cl. 274—47)

This invention relates to phonographic machines and more particularly to improvements therein for reducing record noises in the operation of these machines. The invention is especially concerned with devices in these machines for removing from the records thereof dust and other loose random particles such as will cause record noises and other defects in the phonograph operation.

My invention is particularly applicable to phonographs of the type wherein a recordation is made on a wax-like record by the process of cutting sound-modulated grooves into such a record. In machines of this type there is an especially great need for record-cleaning devices as many of the record particles which are cut from the record body in the recording process adhere to the recorded surface of the record and cause a high level of record surface noise when the recordation on the record is reproduced. To clean the record of the cut-away record portions, and of dust, dirt, or other loose random particles such as will normally collect on the record, it is customary to sweep the record surface with a suitable brush during the course of the machine operation. These brushes tend, however, to become loaded with the particles which are swept from the record and thus, in time, to lose their effectiveness.

It is an object of my invention to cause record cleaning devices in phonographs to be maintained at or near maximum effectiveness throughout their normal use, and to effectively accomplish this result by relatively simple structure.

It is another object to provide a phonograph with means to discharge automatically a record cleaning device or brush of the particles collected thereby.

It is a further object to cause this discharge to occur at appropriate intervals without the need for any special attention or manipulation on the part of the user of the machine.

It is still another object of my invention to restore record cleaning devices to effective condition by the use of means actuated in the normal course of operation of the machine. In this respect it is a feature of my invention that this restoration be effected as an incident of the movement or operation of any appropriate element of the phonograph which is driven or manually moved in the course of the phonograph operation.

Other and allied objects lie in the various combinations of elements hereinafter described and

will more fully appear from the following description and the appended claims.

In the description of my invention reference is had to the accompanying drawings, of which:

5 Figure 1 is a vertical sectional side view of a phonograph in which one embodiment of my invention is incorporated;

10 Figure 2 is a rear view of a portion of the mechanism shown in Figure 1, with parts appearing in section on the line 2—2 of that figure;

Figure 3 is a vertical sectional side view of a phonograph generally similar to that of Figure 1 but showing a second embodiment of my invention incorporated therein;

15 Figure 4 is a rear view of a portion of the mechanism shown in Figure 3, with parts appearing in section on the line 4—4 of that figure;

Figure 5 is a fractional side elevational view, with parts in vertical section, of a phonograph 20 similar to that shown in Figures 1 and 3 but wherein there is incorporated a third embodiment of my invention; and

Figure 6 is a view illustrating details in the mechanism shown in Figure 5, and taken substantially on the line 6—6 of that figure.

My invention is herein illustrated in connection with a conventional business phonograph or dictating machine which operates on a hollow cylindrical record R typically of a waxlike composition. The record is supported rotatably on a mandrel 1 which is journaled as at 2 in an upright standard 3 of a frame 4 of the machine. Carried on suitable standards of the frame 4—

35 for example, at the left side of the machine on the standard 3—are upper and lower cross rods 5 and 6 on which a carriage 7 is slidably mounted.

The mounting of the carriage on the upper rod 5 is made through a long sleeve 8 (partially shown in Figure 2) which is flanged at one end 40 and secured to the carriage by screws 8', and the mounting on the lower rod 6 is effected by the direct slideable engagement of a slotted portion of the carriage with the rod. The carriage comprises a hollow rearward portion through which the rods 5 and 6 pass and in which certain operating mechanism is housed as is hereinafter explained, and a forward arm which overlies the supported record R and which carries a translating device 9. A feeding movement of the carriage 45 along the rods 5 and 6 is produced by means of a feed screw 10 and a cooperating feed nut 11 of which the feed screw is rotatably supported at its ends in the standards aforementioned and the feed nut 11 is movably mounted

50 on the carriage—as through a bracket 21 pivoted

55 on the carriage—as through a bracket 21 pivoted

to the carriage on a rod 28—and is biased into engagement with the feed screw by a tension spring 29 between the bracket 27 and a rod 30 on the carriage. The translating device 9 is adapted to cooperate with the record R to record thereon and reproduce therefrom, it being understood that during a recordation or reproduction the mandrel 4 and feed screw 10 are rotated concurrently to effect a relative progressive movement between the translating device and the record, the rotating means for the mandrel and feed screw being however not herein necessary to show.

The translating device 9 may be of any suitable variety for recording on or reproducing from the record R, or for performing both of these functions selectively. In the present instance, to fully illustrate the application of my invention, the translating device 9 is shown as operable either to record or reproduce and of a type which, in recording, operates to produce a sound modulated groove in a record body by a cutting operation. The translating device here shown, being of an acousto-mechanical form, has a sound box 12 provided with a stylus holder 13 in which there is mounted a recording stylus 14. The sound box is pivotally connected to a frame 15 through an arm 16 on the sound box and a lug 17 depending from the frame at the front thereof, the arm being pivoted to the lug as at 18. Sound communication to and from the sound box is had by way of a tubular neck 19, which extends up from the frame 15, and a tube 20 which couples the neck to the sound box, the coupling between the tube 20 and sound box comprising a spherical flange 20' on the tube and a dome 12' on the box which cooperate to form a universal joint. Beneath the sound box 12 there is provided a biasing weight 21 which has a universal coupling with the lug 17 to permit the weight to move both vertically and laterally in relation to the frame of the translating device, the weight having an arm 21' pivoted at 18 to provide its vertical freedom of movement and a pivoted connection 18' with the arm to provide its lateral freedom of movement. This weight is centrally apertured, as at 22, to permit the recording stylus 14 and its holder to pass therethrough. Pivoted to the weight at 24 is a lever 23 which extends through the weight and which carries a reproducing stylus 25.

When the translating device is conditioned for recording, both the sound box and weight occupy lowered positions wherein they are supported by the record, the sound box being supported by way of the recording stylus and its holder and the weight being supported through an advance ball 26 which glides on the record surface, the weight however performing no useful function in the present instance. When the translating device is conditioned for reproducing, the sound box is held in a raised position as is hereinafter explained, and the weight is held by the lever 23 in an intermediate position between the record and sound box, the lever being supported at its one end by the stylus holder 13 and at its other end by the record through the reproducing stylus, and the weight being held in a floating condition and serving to bias the reproducing stylus against the record.

As shown in Figures 1 and 2, the conditioning of the translating device, and the coupling of the feed nut with the feed screw, are each controlled by a lever 31 which is pivoted to the sleeve 8

within the hollow carriage portion, the lever projecting upwardly through an opening 32 in the top of the carriage so as to be manually accessible. The operative connection between the control lever and the feed nut comprises a cross rod 33, which is carried by the lever between two legs 34 projecting from the hub thereof, and a cam arm 35 on the bracket 27 of the feed nut which is cammed by the rod 33 as the lever 31 is rocked on its axis. The operative connection of the control lever 31 to the translating device comprises the rod 33 just mentioned and a pair of lifting fingers 36 and 37. These fingers are pivoted on the rod 28 and respectively provided with cam portions 36' and 37' which are held in contact with the rod 33 by tension springs 38 and 39 connected between upright extensions 36'' and 37'' of the fingers and the rod 30. The lifting fingers extend angularly forwardly into positions to engage respective tabs 40 and 41 provided on the sound box and biasing weight respectively. The camming of the rod 33 on the cam arm 35 and of this rod on the lifting fingers 36 and 37, as the control lever 31 is rocked on its axis, is such as to effect the following control action:

When the lever 31 is in a forward position—the position occupied by the lever in the figures and herein referred to as its "recording" position—the rod 33 is held free of the cam arm 35 and the feed nut is held in engagement with the feed screw 10 by the spring 29; the rod 33 however bears against the lifting fingers 36 and 37 and holds them down out of contact with the sound box 11 and biasing weight 21 which, being thus free of the lifting fingers, are held by gravity on the record to maintain the translating device in its condition for recording. As the lever 31 is rocked rearwardly into a central or neutral position the rod 33 engages the cam arm 35 and rocks the bracket 27 to disengage the feed nut from the feed screw, the rod coming into engagement with a notch 35' to detain the lever in this central position; also, the rod 33 slides downwardly along the cams 36' and 37' and frees the lifting fingers to move upwardly, in response to their biasing, to raise the sound box 12 and biasing weight 21 and place the translating device in inoperative condition. As the control lever is moved further rearwardly into a terminal position—the position hereinafter referred to as its "reproducing" position—the rod 33 moves free of the cam arm 35 and the feed nut is again engaged with the feed screw by the action of the spring 29; also the rod moves along a dwell of the cam 36' to cause the lifting finger 36 to remain raised and retain the sound box in raised position, but the rod engages a turned back portion of the cam 37', which is of a V-shape, and cams the lifting finger 37 downwardly out of contact with the biasing weight, the weight being thus rendered effective to bias the reproducer stylus against the record and maintain the translating device in reproducing condition. As the control lever is next rocked forwardly a reverse action will take place: the translating device being restored to inoperative condition and the feed nut being disengaged as the lever is returned to neutral position, and the translating device being returned to recording condition and the feed nut being reengaged with the feed screw as the control lever is returned to recording position.

For the purpose of cleaning the record surface of dust and particles cut from the record body during recording, there is provided a brush 50.

This brush is made up of any suitable soft fine strands such as of hair, fibers or the like—for example, of pony or camel hair—and is mounted on the carriage 1 so as to be carried along the record with the translating device. The brush is held in contact with the rotating record and carried therealong during recording and reproducing. Thus the brush is moved progressively across the surface of the record to clean the record by a sweeping action. This action however, being one in which the particles swept from the record are collected by the brush, causes the brush to become loaded in time with these particles and to lose its effectiveness.

To prevent this loss in effectiveness of the brush, without incurring the need for any special attention or manipulation on the part of the operator, I provide a means to cause the brush to be discharged automatically, at appropriate intervals, of the sweepings collected thereby. It is contemplated in my invention that this discharge occur in the course of the operation of the machine as an incident of the normal operation or actuation of any suitable operative element of the machine. For instance, the discharge means may be actuated by the power of the machine from the driven elements thereof, or by hand in response to the normal manipulations made on the machine in adjusting and controlling it, or when actuated by the power of the machine it may be controlled manually in any appropriate manner through the normal manipulations made on the machine. Furthermore, while my invention is not necessarily restricted to any particular positioning of the brush and record, it is preferred that the brush operate on a surface portion of the record which is at an incline with the horizontal or which constitutes a lower or bottom portion of the record in order that the sweepings may be easily kept off the record as they are discharged from the brush. In the case of cylindrical records, the brush may operate on any lower portion of the record—for example, on the back side of the record as shown in the figures—while yet permitting an easy and proper disposal of the sweepings.

In Figures 1 and 2 there is shown an embodiment of my invention which is both manually controlled and manually actuated. In this embodiment, the brush 50 is pivoted to the back part of the carriage 1, it being clamped by a screw 51 to a bail member 52 which is pivoted to the carriage on a rod 53. This pivoting of the brush permits the brush to swing from an effective position—the substantially horizontal position occupied by the brush in the figures—to an ineffective position away from the record such for example as the downwardly inclined position represented by dash-dot lines in Figure 1. The brush is held in effective position whenever the translating device is in operative condition either for recording or reproducing, by the abutment of an arm 52' on the bail member 52 with a rearward projection 54 on the lifting finger 37. When the translating device is shifted to inoperative condition the projection 54 is however moved free of the arm 52', by the upward or clockwise movement of the lifting finger 37 which occurs in such shifting of the device, and the brush is moved down into ineffective position in response to its weight biasing. This shifting of the brush to ineffective position is for the purpose of getting it suitably away from the record to permit it to be readily discharged of the sweep-

ings collected thereby without getting these sweepings back onto the record.

The means in this embodiment for discharging the brush of its sweepings comprises a toothed member 55 which is disposed along the path of the carriage and secured to the frame 4 by screws 56. A movement of the carriage along the record—for example, a backspacing movement such as is manually performed in the course of reproducing portions of previously recorded matter and in the restoration of the translating device to initial or start position to condition the machine for operation on a newly mounted record—will cause the strands or hair of the brush to be swept across the teeth of the member 55, the strands being first deflected and then released as they are moved free of the member 55. As the strands are so released they are flicked—i. e., sprung back to normal position with a quick sharp movement by their own resilience. This flicking of the strands causes the sweepings thereon to be shaken off or discharged. The spacing between the teeth of the member 55 may be chosen at suitable intervals such as is for example indicated in Figure 2.

In Figures 3 and 4 there is shown a second embodiment of my invention which is also manually controlled and operated. This embodiment is herein shown in connection with a phonograph proper which is substantially the same as that shown in the prior figures and wherein like parts are given the same reference characters and new parts are given new reference characters. The brush 50, which is slightly altered in respect of its holder and given the reference character 50a, is in this case rigidly held in effective position by a screw 60 which clamps the holder of the brush to the carriage.

The means to discharge the sweepings from the brush 50a comprises a bail 61 which is pivoted to the carriage, at a point above the brush holder, on a cross rod 62. The bail is controlled by the lifting finger for the sound box 12, which finger—being slightly altered from the analogous finger 36 of the prior embodiment in that a pivot ear 63 is added—is referred to as 36a. The coupling between the bail and lifting finger 36a comprises a short arm 64 on the bail and a link 65 pivoted at 66 to the arm 64 and at 67 to the ear 63 of the lifting finger. As so coupled the bail is caused to pass laterally through the brush as the lifting finger 36a is moved to raise and lower the sound box 12, the bail being swung downwardly and upwardly as the finger is raised and lowered. The movement of the bail through the brush causes the strands thereof to be flicked as in the manner above described in connection with my prior embodiment, and to be freed of the particles adhering thereto. Since the lifting finger 36a is operated with each shift in the conditioning of the translating device between inoperative and recording conditions every such shift will cause the brush to be discharged of the sweepings collected thereby. Thus in placing the machine into and out of condition for recording, as in a normal recording operation and in reproducing a portion of previously recorded matter while in a course of a recording operation, the brush will be discharged automatically of its sweepings.

In Figures 5 and 6 there is shown a third embodiment of my invention which is controlled manually but actuated by the power of the machine. This embodiment is herein shown in connection with a phonograph proper which is also substantially the same as that shown in the prior

figures and wherein like parts are given the same reference characters and new parts are given new reference characters. Several analogous parts which appear here in slightly altered form are however given the old reference characters with the addition of the letter *b*.

In this third embodiment a record brush 50b, which is altered only in respect of its holder, is resiliently supported in effective or operative position on a cantilever spring 70. This spring is secured by a screw 71 to the phonograph carriage which, being somewhat differently shaped in its rearward portion, as will hereinafter be apparent, is referred to as 7b. In this embodiment, the brush 50b is moved impulsively or jarred, at intervals, so as to cause the strands thereof to be shaken or flicked and freed of the particles swept from the record. This jarring of the brush is effected automatically during the operation of the machine in response to the driven movement of the carriage along the record. The means to so jar the brush comprises a cantilever spring 72 which is secured to the carriage, by the screw 71 aforementioned, and loaded at its end by a weight 73. This weight has a central aperture 74 through which loosely extends the holder of the brush 50b, the aperture 74 being elongated in a vertical direction to permit an up and down movement of the weight in relation to the brush. When the spring 72 is in a free unbiased state the weight contacts the holder of the brush at the top of the aperture 74. To impart an impulse to the brush the spring 72 is charged or biased in an upward direction, the weight being moved in relation to the brush substantially through the length of the aperture 74, and then the spring is released to move the weight downwardly under the influence of its biasing. The weight is thus caused to strike the holder of the brush with an impact, which impact will cause the hair of the brush to be flicked and the sweepings adhering thereto to be discharged.

The charging of the spring 72 at regular intervals in the driven movement of the carriage is effected by a ratchet-toothed bar 75, which is carried by the carriage support rod 6b in a groove provided therein, and a pin 77 on the spring 72 which extends through an opening 78 in the rearward portion of the carriage into engagement with the bar 75. The bar 75, which is clearly shown in Figure 6, may have the teeth thereof spaced at any desired intervals as, for example, at about $\frac{1}{2}$ inch intervals as shown in this figure. The teeth of the bar 75 are of such height as to cause an effective charging of the spring and to permit full free release of the spring as the pin 77 slides off from each tooth.

In order that a free manual movement of the carriage may be permitted while the translating device is in inoperative condition, there is provided a means to move the spring 72 operatively free of the bar 75 as the translating device is shifted from operative to inoperative condition. This means comprises the lifting finger for the biasing weight 21 which, being somewhat altered from its shape in the prior embodiments of my invention, is referred to as 37b. On this finger there is provided a downward projection 79 which carries a cross pin 80 at the lower end thereof; and on the weight 73 there is pinned, as at 81, an angular arm 82 which has an upper horizontal portion overlying the pin 80. When the control lever 31 is rocked from either recording or reproducing position into neutral position, the up-

ward movement of the lifting finger 37b, which accompanies such rocking of the control lever, will cause the pin 80 to engage the lower side of the arm 82 and to raise the spring 72 into an upward position wherein the pin 77 is held free of the ratchet-toothed bar 75. Upon restoring the translating device to operative condition the reverse action from the above takes place and the spring 72 is again brought into operative association with the bar 75.

While I have herein shown and described my invention in terms of certain preferred embodiments it will be understood that these embodiments are merely illustrative and not limitative of my invention as they are subject to many modifications and changes without departure from the scope of my invention, which I endeavor to express according to the following claims.

20 I claim:

1. The combination with a phonographic mechanism operable to record on a moving record, of a brush held in contact with the moving record to sweep the surface thereof free of dirt or loose particles; and means, associated with said mechanism and actuated intermittently in the course of a recording operation, for cleaning said brush of the sweeping collected thereby.

2. In a phonograph having a movable record support: the combination of a mechanism operable to record on and/or reproduce from a moving record carried by said support, comprising a plurality of movable parts each operated in the course of operation of the machine; a device associated with the supported record for collecting dirt or loose particles from the surface of the record; means operable to discharge said cleaning device of the loose particles collected thereby; and a coupling between said discharge means and one of the said movable parts of said mechanism for causing said discharge means to be operated by said one part.

3. In a phonograph having a movable record support and a mechanism operable to record on and/or reproduce from a moving record carried by said support: the combination with an operating part included in said mechanism of a brush held in contact with the moving record to sweep dirt or other loose particles from the surface thereof; means operable to flick the strands of said brush to discharge therefrom the sweeping adhering thereto; and means for causing said flicking means to be operated by said operating part.

4. In a phonograph including a recording mechanism adapted to operate on a wax-like record to cut sound-representing grooves therein: the combination with an operating part included in said recording mechanism, of a brush held in contact with the record to sweep therefrom loose record portions cut from the record in the recording process; and means, coupled with said operating part and operated automatically in the course of a recording operation, for flicking the strands of said brush whereby to discharge therefrom the loose record portions collected by the brush in its sweeping action.

5. In a phonograph including a record support, a translating device adapted to cut sound-representing grooves in a record carried by said support and drive means to effect a relative progressive movement between the record and said device: the combination of adjusting means associated with said device to place it into and out of operative association with the record; a brush

moved during recordation by said drive means in relation to the record to sweep the surface thereof free of loose record portions and other particles; means actuatable to flick the strands of said brush to discharge the particles collected thereby in its sweeping action; and means, controlled by said adjusting means, for causing a recurrent actuation of said flicking means.

6. In a phonograph having a movable record support and a translating device adapted to cooperate with a record on said support: the combination of an operating mechanism for effecting a progressive movement between a supported record and said device; a brush held in contact with the moving record to sweep the surface thereof free of dirt or loose particles; means operable to flick the strands of said brush whereby to shake off the loose particles collected thereby; and means, actuated by said operating mechanism, for causing an intermittent operation of said flicking means.

7. In a phonograph having a movable record support and a translating device adapted to cooperate with a record on said support: the combination of means associated with said device to adjust it into and out of operative relationship with a supported record; a brush associated with the record to sweep the surface thereof free of dirt and loose particles; and means, controlled by said adjusting means, for causing the particles collected by said brush to be discharged therefrom.

8. In a phonograph having a movable record support and a translating device adapted to cooperate with a record on said support: the combination of means associated with said device to adjust it into and out of operative relationship with a supported record; drive means for effecting a relative progressive movement between the record and said device; a record brush; and means, actuated intermittently by said drive means and controlled by said adjusting means, for intermittently subjecting said brush to a cleaning action.

9. The combination with a phonographic translating device, of means associated with said device for adjusting it into and out of operative relationship with a moving record; a brush in surface contact with the record for sweeping dirt or loose particles from the surface thereof; and means, controlled by said adjusting means, for causing the strands of said brush to be shaken whereby to discharge the particles collected thereby.

10. The combination with a phonographic translating device, of means associated with said device for adjusting it into and out of operative relationship with a moving record; a brush in surface contact with the record for sweeping dirt or loose particles from the surface thereof; and means, coupled with and actuated by said ad-

justing means in each adjustment of said device, for causing the strands of said brush to be shaken and discharged of the particles collected thereby.

11. The combination with a phonographic translating device of drive means for moving said device progressively in relation to a rotating record; a brush in surface contact with said record for sweeping dirt or loose particles from the surface thereof; and means, actuated by said drive means at intervals in the travel of said translating device, for causing the strands of said brush to be shaken whereby to free the same of the loose particles collected thereby.

12. The combination with a phonographic translating device of drive means for effecting a progressive relative movement between said device and a record with which said device cooperates; means associated with said device for adjusting it into and out of operative engagement with the record; a brush in surface contact with the record for sweeping dirt or loose particles therefrom; and means, actuated by said drive means and controlled by said adjusting means, for causing an intermittent flicking of the strands of said brush whereby to discharge the particles collected thereby.

13. In a phonograph including a record support, a translating device adapted to cooperate with a record on said support and a carriage supporting said device and movable across the record: the combination of means associated with said device for adjusting it into and out of operative relationship with the record; a brush carried by said carriage and positionable into and out of surface contact with the record; means operative upon moving said carriage across the record while said brush is out of surface contact with the record for causing the brush to be cleaned of the particles collected thereby; and means, operatively intercoupling said adjusting means and brush and actuated upon placing said device into and out of operative relationship with the record, for moving the brush into and out of surface contact with the record.

14. The combination with a phonographic translating device mounted for movement in relation to a record, of a brush held in sweeping relation with the surface of the record and carried with said device; means actuatable to shake the strands of said brush and free the same of the sweeping collected thereby; and means for causing said shaking means to be operated by the movement of said device across the record.

15. The combination of a phonograph carriage movable in relation to a record; a brush in surface contact with the record; means to flick the strands of said brush; and means for causing a recurrent actuation of said flicking means by the said movement of the carriage.

CHARLES HUENLICH.
